(57) **CLAIM**

The ornamental design for a baby bottle, as shown and described.

DESCRIPTION

FIG. 1 is a perspective view of a baby bottle, showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

In the drawings, the equal-length broken lines depict portions of the baby bottle which form no part of the claimed design.

The broken line showing of a baby bottle or portion thereof illustrates portions of the article and does not form part of the claimed design.
